R. L. HUNTER.

FLASHLIGHT.

APPLICATION FILED FEB. 18, 1921.

1,392,165.

Patented Sept. 27, 1921.

Robert L. Hunter,

By William L. Dymon

Attorney

UNITED STATES PATENT OFFICE.

ROBERT L. HUNTER, OF NORFOLK, VIRGINIA.

FLASHLIGHT.

1,392,165.

Specification of Letters Patent. Patented Sept. 27, 1921.

Application filed February 18, 1921. Serial No. 445,922.

To all whom it may concern:

Be it known that I, ROBERT L. HUNTER, citizen of the United States of America, residing at Norfolk, in the county of Norfolk and State of Virginia, have invented 5 certain new and useful Improvements in Flashlights, of which the following is a specification.

My invention relates to the construction of 10 flashlights, searchlights, spotlights, or similar devices in which electric lights or other lighting means are used.

The object of this invention is to increase 15 the efficiency and usefulness of searchlights at a small cost and without the use of complicated or easily injured parts. By the use of my invention, the point on which the light from a flashlight may be effectively focused may be changed within reasonable 20 distances without moving the flashlight itself, by varying the distance of the lens from the light. The usual type of electric flashlight has an incandescent light, a concave reflector placed back of the light, and 25 a lens usually plano-convex in front of the light. As the light passes through the lens it is refracted; and since the lens is commonly placed close to the source of light, the emerging rays are widely dispensed and 30 light up a relatively large area a short distance in front of the flashlight. A further object of my invention, therefore, is to make it possible to reduce when desired the diameter of this lighted area and to focus the 35 light on a small area removed from the end of the flashlight, without changing the location of the light, but by changing the relative locations of the light and the lens.

With the usual type of flashlight, if an 40 object to be examined in the dark is a foot or two from the light end of the flashlight, the object is thoroughly illuminated; but if it is at a greater distance, the illumination is diffused and consequently the light is 45 indistinct. By the use of my invention the light from a flashlight may be focused near the end of the flashlight, at a considerable distance from the end of the flashlight, or at any intermediate point.

With these and further objects in view, I 50 have illustrated an embodiment of my invention in the accompanying drawings, in which,

Figure 1 is a side elevation of my im-

proved flashlight, with the lens holding part 55 in section;

Fig. 2 is a vertical sectional view of a part of the light end of my flashlight;

Fig. 3 is a sectional view on the line 3—3 of Fig. 2;

Fig. 4 is a diagrammatic illustration of the principle on which the conventional form of flashlight operates;

Fig. 5 is a diagrammatic illustration of the principle on which my flashlight operates;

Fig. 6 is another diagrammatic illustration of the principle on which my flashlight operates.

The cylindrical case 1 of the flashlight 70 for the battery generally used, which is not shown, has a screw cap 2 on the rear end and a long screw threaded cap 3 on the front end of the case which of course is also screw threaded. There are the usual 75 conventional parts of a flashlight comprising a switch button 4, an incandescent light 5, reflector 6, and lens 7.

The cap 3 is made long and screw threaded 80 in order that the lens in the end of the cap 85 may be placed away from the light as illustrated in Figs. 5 and 6, by simply unscrewing the cap. The maximum distance the lens can be placed from the light is reached 85 when the springs 8 attached to the case 1 cause the points 9 thereof to enter the openings 10 in the cap 3. The cap 3 may of course be removed from the case if desired, by pressing down the points 10 as the cap 90 is screwed off.

The principle of my invention and the means of operating it, will be apparent from the foregoing description. When the user of a flashlight made according to my invention, desires to concentrate the rays of light 95 or desires an intense light at a distance from the front of the flashlight, he simply unscrews the cap until the light is properly focused on the object desired to be illuminated. The cap may be returned to its normal position merely by screwing it in the opposite direction.

I do not wish to be understood as limiting myself to the precise construction and arrangement of parts shown, but claim the 100 right to all changes and modifications within the scope of my invention.

Having now described my invention, what

I claim as new, and desire to secure by Letters Patent, is—

1. Means for changing the focus of the light of a flashlight comprising a flashlight case, a spring attached to said case having a pointed extension on the end thereof, a screw threaded cap for said case, and a lens carried by said cap, said cap having an opening therein to register with the pointed extension on the end of said spring when said cap reaches a certain point on said case.
- 10 2. Means for changing the focus of the

light of a flashlight, comprising a flashlight case, a cap for said case, means adapted to permit said cap to travel on the said case, and means attached to said case and coöperating with said cap to stop automatically the outward travel of said cap, said means being further adapted to be manually operated to be moved to a non stop position to allow separation of said cap from said case.

In testimony whereof I affix my signature.

ROBERT L. HUNTER.
